John F. Standish
By his Attorney,
Nelson W. Howard

UNITED STATES PATENT OFFICE.

JOHN F. STANDISH, OF WINTHROP, MASSACHUSETTS, ASSIGNOR TO UNITED SHOE MANUFACTURING CORPORATION, OF PATERSON, NEW JERSEY, A CORPORATION OF NEW JERSEY.

HEEL HOLDER.

Application filed April 2, 1925. Serial No. 20,211.

This invention relates to heel holders and particularly to heel holders of the type with which heel attaching machines are equipped for holding and locating a heel or parts of 5 a heel in position to be attached to a shoe.

The object of the invention is to improve the construction of heel holders, with a view to increasing the accuracy of the location of the heel or heel parts, the range and variety 10 of work which can be handled, and the ease and speed with which changes to accommodate heels of different sizes and shapes may be made.

The illustrative device herein shown is 15 particularly designed to deal with two-part heels, one example of which is a heel comprising a rigid base section and a rubber top section, commonly called a rubber heel. The utility of the invention, however, is not 20 limited to two-part heels inasmuch as it will be apparent to those skilled in the art that some of its features are equally applicable to a holder for a unitary heel or a single heel section.

25 In attaching a rubber heel, or heel top section, in a heeling machine, where the heel is liable to be subjected to a considerable degree of pressure, it is desirable that the heel be held rigidly immovable in a holder or form which confines the heel around its 30 entire periphery and which has a depth nearly equal to the height of the rubber heel, to prevent distortion of the heel by the pressure and movement of the nail holes in the 35 heel out of register with the holes in the nailing die of the heeling machine by which the attaching nails are driven. It is customary to provide a so-called "ring", or fixed form, for each size, shape and thickness 40 of rubber heel to be attached, these rings or forms being so mounted in the heel attaching machine that they may be readily interchanged when it is necessary to change from operation upon one size of heel to another.

45 When the sections of a two-part heel are assembled and secured together before they are brought to the heeling machine as, for example, when a rubber heel and a leather heel base are preliminarily assembled and 50 secured together by cement or fastenings of some kind, the heel form of the type referred to constitutes a sufficient holder for the entire heel but if the two sections of the heel are separate and unattached when placed in the

heeling machine it is necessary to provide 55 means for holding the base section as well as the top section. This has also been accomplished by making the heel form of sufficient depth and so shaping the walls of the cavity in it that virtually two cavities are provided, one for the top section and another 60 for the base.

It often occurs, however, that it is desired to use bases of different sizes or shapes with 65 the same size and shape of top section and the provision of a sufficient number of solid forms to cover all the combinations which might occur would not only be prohibitively expensive but the forms themselves would 70 occupy an unreasonable amount of space in the shoe factory. An important feature of the present invention accordingly consists in a heel holder in which provision is made for a fixed form or ring to hold one heel part and a holder is provided for the other heel 75 part which holder is readily adjustable to accommodate and properly locate heel sections of all sizes and shapes within reasonable limits.

Rubber heels of different heights normally 80 require rings or forms of different depths or thicknesses and a further useful feature of the invention consists in the provision of blank edge engaging members at least one 85 of which is adjustable in the direction of the height of the blank. In the specific embodiment of the invention herein illustrated and described, this feature is embodied in a base holder which is adjustable heightwise and may therefore readily be so disposed as to 90 engage properly the edges of a heel base, regardless of the thickness or height of the heel top section upon which it is placed.

In accordance with the invention adjustments are further provided whereby the 95 location of the base longitudinally with respect to the top section or rubber heel may be readily changed to suit the requirements of the work in hand and this adjustment is preferably independent of the heightwise 100 adjustment previously referred to.

These and other features of the invention will best be understood and appreciated by reading the following detailed description in connection with the accompanying drawings illustrating one embodiment thereof but it should be understood that various 105 features of the invention might be embodied

in other specific forms of construction without departing from its spirit and intent.

In the drawings,

Fig. 1 is a plan view of a heel holder embodying the invention;

Fig. 2 is a vertical longitudinal section on the line 2—2 of Fig. 1; and

Fig. 3 is a transverse section on the line 3—3 of Fig. 1.

10 The holder herein shown is designed to be mounted upon a heelng machine in the same manner as the heel holder shown in my prior Patent No. 1,365,802, Jan. 18, 1921, and, as shown, may indeed be substituted 15 bodily for the holder shown in the said patent, to which reference may be had for details of its mounting and relation to the other operating parts of the heelng machine.

20 Referring now to the drawings, 16 and 18 indicate respectively the nailing die supporting member and the nailing die of a heelng machine and 24 indicates a stationary horizontal guide bar upon which the 25 entire heel holder is supported and guided for movement by a guide slot 68 (Fig. 2) cooperating with a stationary roll at the front of the nailing die supporting member. These parts all correspond to parts 30 bearing the same reference numerals in the patent above referred to, as do the latch arm 64 and latch shaft 54 whose function is fully described in said patent.

35 The sliding form carrier comprises a casting 10 which is provided with guides 12 in which may be removably secured a heel ring or form 14 having a cavity shaped to fit the rubber heel to be attached. An interchangeable series of these forms is provided to 40 accommodate all the different sizes and shapes of heels to be handled. The form is secured in position in the carrier 10 by a pin 20 which is normally held in securing position by a spring 22 but which may be 45 readily withdrawn to permit the changing of forms. The end of the pin 20 is tapered as shown at 26 so that the form will always be located in the same position in the holder regardless of wear upon the parts.

50 Superposed upon the form 14, which constitutes a fixed holder for a rubber heel or heel top section, is an adjustable holder for the base deck of a heel which will now be described in detail. A pair of fingers 28, 55 shaped to engage the edges of the blank adjacent to its breast corners, are pivoted to swing upon bolts 30 and are geared together as shown at 32 for equal and opposite movement to ensure that the blank shall be centered transversely. One of the fingers 28 is provided with a laterally extending arm 34 to which is pivotally connected a rod 36 having threaded upon its outer end an adjusting nut 38. The rod 36 is surrounded by a 60 compression spring 40 of which one end

bears against the arm 34 and the other end against a bracket 42, causing the fingers 28 normally to move toward each other to a limit determined by the adjustment of the nut 38.

70 The bracket 42 is integral with a carrier 44 in which the pivot bolts 30 are secured. The carrier 44, with the swinging fingers 28 carried thereby, is pivotally movable about the horizontal axis of a pin or rod 46 secured in lugs 48 formed on a slide 50 guided for rectilinear adjustment forwardly and rearwardly in suitable ways in the casting 10. This adjustment is effected by a screw 52 threaded into the casting 10 and having 80 a manually operable adjusting knob 56 between which and a collar 58 is located a projection 60 depending from the slide 50.

85 The position of the carrier 44 and the fingers 28, considered vertically, is determined by an adjusting screw 62 threaded through the rear end of the carrier and bearing upon the top of the slide 50 and a spring 66 (Fig. 2) which tends to elevate the front end of the carrier and the fingers 28.

90 From the foregoing it will be understood that the blank edge engaging fingers 28 are adjustable forwardly and rearwardly with respect to the cavity in the heel form 14 by means of the screw 52 and are adjustable 95 heightwise, both bodily and in relation to the form 14, by means of the screw 62.

99 The heel base, which is indicated in the drawings by the numeral 69, is additionally held and located by a forked rear gage 70 which is carried by an approximately horizontal stem 72 slidable forwardly and rearwardly of the holder in an adjustable bushing 74 and surrounded by a compression spring 76 which tends to move the rear gage 70 forward. The bushing 74 is threaded into a rocker member 78 which is pivoted upon a transverse horizontal axis in lugs 80 integral with a bracket 82 which, in turn, is integral with the casting 10.

105 The position of the rocker member 78 and, consequently, of the rear gage 70, in a vertical sense, is determined by adjustment of a screw 84 threaded through the bracket 82 against which screw the forward end of the 110 rocker member 78 is held by a spring 86 (Fig. 2).

115 It will be understood that the rear gage 70 is really mounted in the bushing 74, being yieldable rearwardly with respect to its 120 mounting by reason of the spring 76, and that the gage is adjustable forwardly and rearwardly with respect to the opening in the heel form 14 by adjustment of the bushing in the rocker member 78. Furthermore, 125 heightwise adjustment of the rear gage 70 is effected by turning the screw 84 to the desired point.

130 By proper adjustment of the transverse space between the fingers 28 and the longi-

tudinal position of the rear gage 70 with respect to said fingers, the base holder may be made to accommodate a heel section of any size or shape and by proper adjustment

5 of both the fingers 28 and the rear gage 70 longitudinally of the holder the base section may be positioned as desired in relation to the rubber heel in the form 14. Furthermore, heightwise adjustment of both the 10 fingers 28 and the rear gage 70 may be readily effected to cause them to engage the edges of a heel base section at a height to hold it most advantageously and to accommodate heel forms 14 of different thicknesses which may be required for rubber 15 heels of different heights.

Having described the invention, what is claimed as new and desired to be secured by Letters Patent is:

20 1. A holder for multi-section heels having, in combination, a holder for one heel section, a separate holder for another heel section superposed upon the first, and means for effecting relative adjustment of said holders 25 in the direction of the height of the heel.

2. A holder for two-part heels having, in combination, a holder of fixed size for positioning and holding the top deck of a heel by engagement with its edges, and an independent holder adjustable in size for the 30 base deck of the heel, one of said holders being superposed upon the other.

3. A holder for two-part heels having, in combination, a holder of fixed size for positioning and holding one heel part by engagement with its edges, and an independent holder adjustable in size for the other heel part, one of said holders being superposed upon the other.

40 4. A holder for holding two parts of a heel in horizontal positions and superposed arrangement having, in combination, a stationary holder for positioning and holding one of the heel parts by engagement with its 45 edges and a separate holder for the other

heel part which is bodily adjustable horizontally in relation to the first-named holder to vary the relation between the two heel parts.

5. A holder for holding two parts of a heel in horizontal positions and superposed arrangement having, in combination, a holder for positioning and holding one heel part by engagement with its edges and a separate holder for the other heel part which is bodily adjustable heightwise in relation to the first-named holder to accommodate heel parts of different heights.

6. A holder for holding two parts of a heel in horizontal positions and superposed arrangement having, in combination, a holder for positioning and holding one heel part by engagement with its edges, and a separate holder for the other heel part which is bodily adjustable both heightwise and horizontally in relation to the first-named holder to vary the position of one heel part upon the other and accommodate heel parts of different heights.

7. A holder for separate parts of two-part heels having separate breast engaging members for the two heel parts, said members being relatively movable toward and from each other in the direction of their height.

8. A holder for separate parts of two-part heels having a breast gage for one of the heel parts and separate breast engaging members for the other heel part, said members being movable toward and from each other and toward and from said gage in the direction of its height.

9. A heel blank holder having a breast edge engaging member and a rear gage relatively movable toward each other to hold a heel blank by its edges, both said member and said gage being adjustable heightwise of the blank independently of each other.

In testimony whereof I have signed my name to this specification.

JOHN F. STANDISH.
